The ornamental design for an extrusion for window and door frames, as shown and described.

DESCRIPTION

FIG. 1 is a perspective view of an extrusion for window and door frames showing my new design;
FIG. 2 is a right side elevational view thereof;
FIG. 3 is a left side elevational view thereof;
FIG. 4 is a top plan view thereof;
FIG. 5 is a bottom plan view thereof; and
FIG. 6 is a front elevational view, the rear elevational view being substantially identical thereto.

FIG. 1

FIG. 2

FIG. 3**FIG. 4****FIG. 5****FIG. 6**
